UNITED STATES PATENT OFFICE.

ALFRED H. DAVIS, OF ST. PETERSBURG, FLORIDA, ASSIGNOR, BY MESNE ASSIGNMENTS, TO INTERNATIONAL CONCRETE PILING CO., INC., OF JAMESTOWN, NEW YORK, A CORPORATION OF NEW YORK.

APPARATUS FOR CONCRETING PILES.

1,198,621.

Specification of Letters Patent. Patented Sept. 19, 1916.

Application filed August 15, 1910. Serial No. 577,365.

To all whom it may concern:

Be it known that I, ALFRED H. DAVIS, a citizen of the United States, residing at St. Petersburg, in the State of Florida, have 5 invented certain new and useful Improvements in Apparatus for Concreting Piles, of which the following is a specification.

This invention relates to an improved process and apparatus for casting concrete 10 jackets around piling or other structures to protect them against the ravages of the teredo or other destructive marine worms and the like: and for the further purpose of reinforcing and strengthening old, decayed 15 or worm eaten piling in docks, piers, bridges, or wherever piling is used.

One of the objects of this invention is to facilitate and lessen the cost of labor in forming a protective covering of concrete 20 upon a submerged, or partially submerged portion of a pile or other similar support, after it has been driven into place, and particularly to enable the concrete covering to be carried down to the bottom of the pile, 25 in its proper consistency and there permitted to set without the intermingling therewith, of the surrounding water.

A further object of this invention is to provide an annular space around the piling 30 below the level of the tide which shall be comparatively devoid of water, and into which may be placed concrete mixed to the proper consistency, without its coming in contact with the surrounding water while it 35 is being tamped in the mold.

Another object of my invention is to provide a receptacle or mold in which the concrete is placed, after having been mixed to the proper consistency by the addition of 40 fresh water, as contra-distinguished from the methods employed wherein the mixture, of cement and gravel is placed in dry form in receptacles and sunk into place, depending on the sea water to effect the chemical action and combination between the ingredients of the mixture, the advantages of which will hereinafter more fully appear.

A further object of my invention is an improved arrangement of the concrete jacket casting apparatus, whereby the said apparatus may be readily detached from the pile with its surrounding concrete

jacket, removed therefrom and placed in position on another pile ready to repeat the jacket casting process.

55

My said invention further relates to a process of covering each section with a coating of non-adhesive compound, which facilitates the removal of the molds after the concrete has become partially set, as well as imparting a smooth exterior surface to the concrete jacket.

My said invention further relates to an improved form of a detachable mold and reinforcing frames of novel construction and 60 arrangement of parts herein described, and more particularly pointed out in the accompanying claims.

In order to more fully describe my said invention, reference will be had to the accompanying drawings in which:

Figure 1, represents in vertical section, a form of apparatus embodying my invention, the same being shown closed and locked ready to receive the concrete mixture: Fig. 75 2, represents a transverse section a reinforcing frame, a tubular mold and an inner-tube. Fig. 3, is a perspective view of sections of an inner tube showing means for joining the two half sections and means for locking the longitudinal sections together. Fig. 4, is a perspective view, with parts broken away, of the reinforcing frame with the tubular mold in position therein. Fig. 5, is a vertical transverse section produced 80 through the first mold section showing the taper funnel shaped bottom. Fig. 6, represents a transverse section open, showing the hinged reinforcing frame with the tubular mold in half sections. Fig. 7, is a sectional 85 elevation taken centrally through a pile, disclosing the application of the apparatus. Fig. 8, is an enlarged view of the locking means whereby the flanged edges of the tubular mold are coupled together. Fig. 9, is 90 a vertical transverse section produced through a section of the reinforcing frame showing its reinforced construction. Fig. 10, represents a transverse section of the reinforcing frame open, disclosing the hinge 100 joint, and the locking latch. Fig. 11, is an enlarged view of one of the clevises by which the sections of the reinforcing frame are joined together.

Like parts are represented by similar characters of reference in the several views.

My apparatus consists of the following parts as shown in Fig. 1, all of which combine to produce a portable mold or form around a pile or other structure, partially or wholly submerged, standing separately or in position in any structure of which they may form a part:

10 The supporting frame consists of a series of horizontal and perpendicular supports reinforced at their intersections by suitable metal plates properly bolted or riveted, the whole being bisected perpendicularly, provided with hinges at one side and an extensible locking device at the opposite side, which provides for securing the frame when the same is being adjusted or lowered into position, and unlocking and removing 15 the same entirely by operations conducted from above the surface of water, thus eliminating the necessity of divers or submarine apparatus. By my improved process and apparatus herein described I make it possible to perform all of the operations necessary to properly concrete-jacket a pile or other support, at a point above the level of the tide.

Referring to the accompanying drawings, 30 1 represents a section of the inner tube; 2 represents a section of the tubular mold form; 3 represents a section of reinforcing and supporting frame.

For the purposes of forming a concrete 35 jacket around a pile I provide one or more jacket-forming units, each of which is comprised in the case shown, of an inner tube immediately surrounding the pile or object to be concrete-jacketed; of a tubular mold 40 section surrounding the inner tube and adapted to receive and contain the concrete; and of a reinforcing and supporting frame adapted to clasp around the tubular mold section for supporting and reinforcing the 45 same during the operation of forming the concrete jacket. The sectional inner tube consists of two half sections by means of which each section is bisected vertically and placed around the pile. The contiguous 50 vertical edges of the two half sections are provided with a tongue and groove joint, and for the purpose of making this joint water tight, I place in the groove of the joint a layer of suitable compressible packing, such as oakum or other material, well 55 known in the art and used for making joints water tight. When the two halves of a section of inner tube have been placed in position around a pile, I provide for joining 60 the next section thereto by telescoping the intersecting joints or divisions of one section with the section below, and to provide means for securely holding the sections together, for the purpose hereinafter explained I provide a hasp and staple 4, 65

shown in Fig. 3. By this means it is possible to construct around a standing pile or other similar structure a tube of any desired length, water tight, and detachable. Around this inner tube is placed the tubular 70 mold section 2, consisting of two half sections bisected vertically as shown in Fig. 5. For the purpose of providing a water-tight joint, the contiguous edges of the tubular mold form are made with extended flanges 5, 75 between which are placed suitable gaskets 6, designed to be compressed by methods hereinafter described, into making a water tight seam in the joint between the two halves of the tubular mold sections. 80

For supporting the tubular mold sections I provide a suitable cage frame 3, which also serves to reinforce the tubular mold, into which the concrete is placed, as shown in Figs. 1, 4, 7, and 9, wherein, 7 represents angle irons, shown riveted to annular shaped hoops 8, placed at suitable intervals. At the intersections of the angle irons 7, and the annular hoops 8, are placed reinforcing plates 9. The annular shaped hoops 8, are provided with a knuckle joint 10, upon which the supporting frame as assembled, opens to receive into and to be clasped around the tubular mold 2. At the intersecting edges of the annular shaped hoops 8, directly opposite to the knuckle joint 10, are provided locking means for latching the two bisected halves, consisting, on the one intersecting edge of latch 11, which engages the latch bar 12, which is 95 slidably mounted at the opposite intersecting edge of the supporting frame, so that when the supporting frame is closed around the tubular mold, the protruding end 13, of the latch 11, passes through a slot in the latch bar 12, and by an upward movement 100 of the latch bar, it lockingly engages the latch 11. 105

In the construction of the supporting frame, the angle irons 7, are placed in pairs as shown in Fig. 4, and are so placed in relation to each other, that the inwardly extending angles are so spaced apart, sufficiently to admit of the flanged lips 5, of the tubular mold section to be placed between 110 the inwardly extended faces of the angle irons, and thereby securely gripping the flanged lips 5, in the closing operation of the supporting frame around the tubular mold. For the purpose of gripping these 115 flanged lips to a greater degree, and thus insuring a water tight joint, I provide set-screws 14, tapped through one of the inwardly extended faces of the angle irons at 120 suitable intervals, and by means of "setting up" these screws I am enabled to compress the gaskets 6, placed between flanged lips 5, thereby making the intersecting joints of the tubular mold sections water tight. The 125 angle irons thus provided with compressing 130

means and which are adapted to engage the flanged lips of the tubular mold are placed at the bisecting line of the supporting frame. For the further purpose of reinforcing the 5 tubular mold, I place similar angle irons 7', at ninety degree intervals from those used for compressing the flanged lips 5, above referred to, which are arranged to engage an angle iron 15, shown on Figs. 2 and 10 4, which is securely bolted to the tubular mold section.

For the purpose of supporting the tubular mold section, I provide angle hooks 16, securely riveted to the tubular mold 2, at the 15 upper and lower extremities thereof, and arranged to rest on the annular shaped hoops 8, of the supporting frame.

For the purpose of handling the supporting frame and swinging the same into position around the pile or other structure above to be cement jacketed I provide hooks 17, securely attached to the supporting frame. To hooks 17, are attached suitable chains or other supporting devices leading upward 25 to the superstructure above the piling from which the apparatus is supported and lowered.

In Fig. 1, is shown the first or lower section of a supporting frame, the upper terminal of which section ends at the annular 30 shaped hoop 8, above the supporting hooks 17. Above this annular shaped hoop is shown the beginning of another section of the supporting frame, and is shown intersected and locked to the lower section by the clevises 18, which are bolted at their upper ends to the annular hoop of the engaging section, and are arranged to slip over the upper annular hoop of the lower 35 section, and are locked by the bolt 19, passing therethrough as shown in an enlarged 40 detailed view in Fig. 11.

For providing a suitable detachable joint for the latch bar 12, at intersections of the 45 supporting frames, I provide an off set joint for bringing the two sections of the latch bar in proper alinement and couple the same with a bolt 20.

In providing a suitable tubular mold section 50 that can be placed around a standing pile I arrange for each section of the tubular mold form to be made in two half sections divided vertically the lower extremities of the first or anchor section being contracted or reduced to funnel shape at its 55 lower end. To provide a suitable means for making the intersecting edges of the two half sections water tight, I provide outwardly extending flanges through which I 60 have provided suitable apertures 21, in the one half section, adapted to engage the protruding studs 22, placed in the other half section, so that when the tubular mold form is closed, the studs 22, pass through the apertures 21, and the cotter pins 23, are

placed through the holes provided therefor, in the stud 22, thus securely locking the two half sections of the tubular mold form together.

For the purpose of creating a water tight 70 joint where the one tubular mold section rests upon and engages the next lower tubular mold section, I provide a suitable lining or apron which is securely fastened to the inner side of the tubular mold sections at 75 line 24, Fig. 5, arranged to telescope into the next lower section to a depth of line 25, shown in Fig. 5. This lining or apron may be made of any suitable material preferably of heavy water proof canvas or other 80 fabric, designed to close in against the inner surface of the tubular section next below by the compressing force of the weight of the concrete mixture. For the purpose of further uniting and maintaining the super- 85 posed sections of the tubular mold casing in alinement, I provide a hasp 26, shown in Fig. 7, on the one section, adapted to engage a staple 27, on the other section, through which is inserted a suitable cotter pin. By 90 this means the tubular casing sections are held together, and may be supported from the superstructure by suitable chains or other means, attached to the staples 27 shown in Fig. 7. 95

I do not limit myself to the specific form or proportionate size of tubular mold or other parts of the apparatus shown in the accompanying drawings as various sizes of molds may be used in the same supporting frame by means of adjusting the extensions therefrom, consisting of the flanges 5, and angle irons 15, and the supporting hooks 16, to properly engage the supporting frame as herein described. 100

Having thus described the various parts of my apparatus in detail, the application of the same is as follows: When a concrete covering is about to be placed around a pile or other support and without removing the 110 planking of the dock or superstructure, upon which the work is to be done, the reinforcing and supporting frame is opened and placed in a horizontal position as shown in Fig. 9. Into this supporting frame is placed the tubular mold section shown in Fig. 5, which has been selected as of the proper diameter sufficient to give the required thickness of the concrete jacket for the particular pile it is to be applied to. To the inner surface of the tubular mold section, I apply a non-adhesive mixture composed of red lead and common brown soap, which facilitates severing the tubular mold sections, from the concrete jacket after it has received its initial set, and also imparts a smoothness to the exterior surface of the concrete jackets. The tubular mold sections are held in proper place in the frame by the supporting hooks 120 125 130 135 140 145 150 155 160 165 170 175 180 185 190 195 200 205 210 215 220 225 230 235 240 245 250 255 the supporting frame. The angle irons 15, are also brought into engagement with the slot provided for in the space between the angle irons 7' 7', receiving a bearing therein against the supporting frame as shown in Fig. 4. The supporting frame, together with the tubular mold forms therein is then closed together and properly latched. In this form it is supported from any cross timber or part 10 of the superstructure by means of chains or other suitable supports, depending therefrom, attached to the hooks 17. The frame in its suspended position, together with the tubular mold form therein is then opened 15 and swung into position around the pile above the water line, and the supporting frame is then closed and latched, and the cotter pins 23, are slipped through the holes into studs 22, thus fastening the edges of the 20 half sections of the tubular mold casing. The set screws for compressing the gaskets 6, are then properly "set up" making the joints water tight. I then place the two halves of a section of the inner tube around 25 the pile, allowing the same to slip down over the pile until the lower edge of the inner tube engages the funnel shaped bottom of the tubular mold section as shown in the dotted lines in Fig. 1, provision being made 30 for placing a gasket on the lower end of the inner tube, where it engages in contact with the funnel shaped end of the tubular mold casing, the weight of the inner tube creating a sufficient bearing upon the gasket 35 to make a water tight joint between the inner tube and the funnel shaped sides of the tubular mold casing. I then place in the annular space formed by the inner tube, and the tubular mold casing, a proper quantity 40 of broken stone or gravel to make a proper foundation upon which the first application of concrete is placed. The annular space between the inner tube and the tubular mold casing, is then filled from above the water 45 line with a concrete mixture of proper consistency. The supporting frame with the inner tube and the tubular mold casing resting therein, is then lowered until the top of the mold casing is a few inches above the 50 water line. I then place another section of the inner tube around the pile with a telescopic joint connecting the same with the like section already in place. I then repeat the process of placing another section of the 55 tubular mold form into another section of the supporting frame and clasping the same around the pile, lowering the supporting frame section until the clevises 18, engage the uppermost annular shaped hoop 8, of the 60 section of the supporting frame already in place, at the same time permitting the inner lining or fabric attached to the lower edge of the tubular mold section, to telescope inside of the lower mold section already in place. I then attach and fasten the

two supporting frame sections together by inserting the bolts 19, through the lower extremities of the clevises, and couple up the two sections of the latch bar 12, by inserting the bolt 20, therethrough. To securely attach the two sections of the tubular mold casing, I place the hasp 26 over the eyelet or staple 27, and insert a cotter pin through the aperture in the staple, thus securely connecting the one section of the tubular mold casing with the section next above. An application of cement or concrete mixture is then applied to the annular space until by such application the concrete has arisen to a point above the fabric apron and 70 properly compressing the same against the inner sides of the next section of the tubular mold form below, thus making a water tight joint between the two mold sections so jointed as aforesaid. The whole apparatus 75 is then again lowered and the process of applying the mold section is repeated and the concrete is continued until the lower or anchor section composing the funnel shaped tubing, reaches the bottom and is embedded 80 sufficiently into the mud or gravel into which the pile is driven to shut off any sea water getting in from below, after which the concreting may be continued to any desired 85 point above the water line. After the required height of the concrete jacket has 90 been provided, the inner tube is immediately withdrawn, allowing the concrete in its plastic condition to settle around the pile without altering to any appreciable extent its proper consistency, and forcing in its settling operation, any water that may have existed in the space between the inner tube and the pile, upwardly and out through and over 95 the top of the concrete. 100

As the inner tube is withdrawn, and the concrete settles and fills up any depressions or worm eaten cavities in the pile, sufficient concrete mixture is added at the top to always keep the level of the concrete above the 110 water line as the tube is being withdrawn, thus providing against any disintegration of the concrete mixture. After the concrete mixture thus applied has established its initial set the reinforcing and supporting frame 3, may be removed, the tubular mold form 2, being left in position until such time as the concrete thus formed around the pile has attained sufficient age and hardness to resist the action of the water in agitation 115 caused by tides, currents, and undertow. After this state has been reached, the cotter pins 23 are withdrawn by suitable chains connected therewith extending upward to a point above the water line. To provide for 120 the drawing of one of these cotter pins at a time and thus drawing the various pins in *seriatim*, I arrange my draw chains connected to the cotter pins in such manner that there is a little slack chain between the fas- 125 130

tening of the chain to the one pin and the fastening of the chain to the pin next below, so that in drawing the uppermost pin no tension is put on the next succeeding pin below, 5 until sufficient movement of the chains has disengaged each upper pin before the drawing of the pin next below commences.

The apparatus herein described may be used in forming concrete covering other than 10 the form which I herein show and the apparatus embodying my invention may be used for concrete coverings to other than piling or analogous marine structures and I do not desire to limit my invention in all 15 cases to the formation of cylinders of concrete around standing piling or the like, since my apparatus may be adapted to cast jackets of other shapes and on other structures without departing from my said invention. 20

What I do claim as my invention is:

1. An apparatus for forming a concrete casing around a driven pile, the combination 25 of a sectional inner tube adapted to encircle a driven pile, a sectional outer tubular casing adapted to be placed in a surrounding supporting frame, locking means for holding said supporting frame in surrounding position, with means for detaching and 30 withdrawing the inner casing, the supporting frame, and the tubular mold casing, separately.

2. In an apparatus for forming a concrete casing around a driven pile, the combination 35 of an inner casing, and an outer mold casing longitudinally divided into semi-cylindrical segments adapted to encircle a pile providing an annular space between said casings constituting a mold in which is formed the 40 concrete casing, a reinforcing frame adapted to be clasped and locked around the outer casing for supporting the mold during the concrete casting operation, with means for unlocking the reinforcing frame actuated 45 from a point above the level of the surrounding water.

3. In an apparatus for forming a concrete casing around a driven pile, the combination 50 of an inner casing, and an outer casing longitudinally divided into semi-cylindrical segments adapted to encircle a pile providing an annular space between said casings constituting a mold in which is formed the concrete casing, a reinforcing frame adapted 55 to be locked in an encircled position for supporting the mold during the concrete molding operation, with means actuated from the point above the level of the surrounding water for unlocking, and remov-

ing, the semi-cylindrical segments substantially as described. 60

4. An apparatus for forming a concrete covering around a pile comprising an inner and outer casing adapted to encircle a pile providing an annular space between the inner 65 casing and the pile, a mold formed between said casings adapted to receive plastic concrete, a reinforcing frame adapted to be locked in an encircled position around the casing, means for withdrawing the inner 70 casing while the concrete is in plastic condition, without destroying the annular formation of the molded concrete.

5. An apparatus for forming a concrete covering around a pile consisting of a sectional inner tube adapted to be opened bisectingly to encircle a pile, a sectional outer tube adapted to be bisected vertically having hinged connections at one of its bisect 75 tions and locking means for holding together the contiguous edges of the other bisection, adapted to form a mold for holding concrete, a supporting frame adapted to house said outer casing, means for opening said sectional outer casing and the supporting 80 frame conjointly to permit of their being clasped around a pile, locking and supporting means for holding said supporting frame, means for withdrawing the inner tube while the concrete is in a plastic condition. 85

6. An apparatus for forming a concrete covering around a pile, consisting of an inner tube bisected vertically and an outer casing longitudinally divided into semi-cylindrical segments, having hinged connections at one of its divisional lines and locking means for holding together the contiguous edges at the other divisional line, compressing means adapted to place the contiguous edges in closer contact, a reinforcing frame adapted to house the outer casing, means for opening said outer casing and the reinforcing frame conjointly to admit of transversely placing the casing around a 95 pile to form a mold in which is placed plastic concrete, means for withdrawing the inner tube while the concrete is in a plastic condition, and means for unlocking the reinforcing frame to facilitate its removal 100 from the outer casing actuated from a point above the level of the water. 105

In testimony whereof I have affixed my signature in presence of two witnesses.
